CLAIM

The ornamental design for a display screen or portion
thereof with graphical user interface, as shown and
described.

DESCRIPTION

The sole FIGURE is a display screen or portion thereof with
graphical user interface showing our new design.

(Continued)

The peripheral dashed broken lines represent a display screen or portion thereof which forms no part of the claimed design.

1 Claim, 1 Drawing Sheet

Matter enclosed in heavy brackets [ ] appears in the original patent but forms no part of this reissue; matter printed in italics indicates the additions made by reissue.

It is certified that error appears in the above-identified patent and that said Letters Patent is hereby corrected as shown below:

On the Title Page

Under item (57), DESCRIPTION

Column 2 insert the following statement in the beginning of the section before the descriptive statement:

--This application is a continuation reissue of U.S. application Ser. No. 29/778,455, which is a continuation reissue of U.S. application Ser. No. 29/671,750, now U.S. Patent No. RE 48,567, which is an application for reissue of U.S. Pat No. D. 772,910, which issued from U.S. application Ser. No. 29/519,785; the entireties of which are expressly incorporated herein by reference.--

Page 2 Column 1 Lines 1-3:

-The peripheral dashed broken lines represent a display screen or portion thereof which forms no part of the claimed design.-

Should read:

--The peripheral dashed broken lines [represent] *depict* a display screen or portion thereof which forms no part of the claimed design.--

Page 2 Column 1 Insert following statements after Line 3:

--The interior broken lines depict portions of the graphical user interface which form no part of the claimed design. The relatively faded gray depicts portions or elements of the graphical user interface which form no part of the claimed design.--
